UNITED STATES PATENT OFFICE.

SAMUEL B. FRANK, OF NASHVILLE, TENNESSEE, ASSIGNOR OF ONE-HALF
TO EDWARD B. POLK, OF SAME PLACE.

PULVERIZER.

SPECIFICATION forming part of Letters Patent No. 447,674, dated March 3, 1891.

Application filed June 11, 1890. Serial No. 355,096. (No model.)

To all whom it may concern:

Be it known that I, SAMUEL B. FRANK, a citizen of the United States, residing at Nashville, in the county of Davidson and State of Tennessee, have invented certain new and useful Improvements in Pulverizers; and I do declare the following to be a full, clear, and exact description of the invention, such as will enable others skilled in the art to which it appertains to make and use the same, reference being had to the accompanying drawings, and to the letters of reference marked thereon, which form a part of this specification.

15 This invention relates to pulverizers, and has for its object the preparation of dirt or sand for brick-machines.

The invention consists in the novel arrangement and construction of the different parts, 20 as will be hereinafter fully described and claimed.

In the accompanying drawings, forming part of this application, Figure 1 is a side elevation of my pulverizer. Fig. 2 is a sectional view thereof; and Fig. 3 is a front view of my semicircular arms carrying the rollers.

Like letters of reference denote like parts throughout the figures.

On the inside of a cast-iron frame A is located a cylinder B, journaled in either side of the frame A and provided with the usual drive-pulley C. The frame A is provided with an ordinary hopper or opening a in the top and suitable legs c. A series of revolving scrapers D, having blades d, are situated inside the frame A, the bottom scraper D' being just at the opening d', from whence the pulverized dirt is deposited. The other scrapers are situated at a given distance from the center of the cylinder B. These scrapers are all arranged in the front portion of the frame A, although there may be one or more such scrapers on the opposite side or on the rear of the machine, as clearly shown in Fig. 2.

45 Between the cylinder B and the scrapers D is located a series of small cylindrical rollers E. These rollers E are journaled at either end in a semicircular arm F, which is fulcrumed at its lower end in the sides of the frame A. The arms F are connected by a

bar f, extending across the machine and rigidly attached to each of said arms. This bar f has a screw-threaded aperture, into which is inserted a screw-threaded adjusting-screw G, having a broad foot g to prevent its becoming separate from the bar f and a wheel-handle H.

A screw-threaded bearing h is formed in the frame A for the adjusting-screw, and by turning the handle of said screw in one direction the bar f and the arms F, carrying the rollers E, will be moved toward the cylinder B, and turning the handle of the adjusting-screw in the opposite direction the rollers E will be moved from the cylinder B.

It will be observed that one scraper D is arranged to scrape the small rollers, while the scraper D' is arranged to scrape the large cylindrical roller B and the lower small roller E', so that each small roller has its outer surface thoroughly scraped. If it is desired to have the dirt made into very fine particles, the adjusting-screw is simply operated, which will bring the top roller near the cylinder B, the next roller will come a degree closer to the said cylinder, while the last or lower roller is still closer to the cylinder, thus making the space between the large cylindrical roller and each of the small rollers less or smaller than the roller above it—that is, the pressure of the small rollers on the dirt or sand is regularly gradated by means of the arm F and bar f, actuated by the adjusting-screw G.

Power is imparted to the large cylinder or roller through the medium of a belt I from an engine to the pulley C. The small rollers and scrapers are driven by suitable connecting-belts to the main pulley C.

I do not wish to be understood as limiting myself to any particular number of small rollers or to the number of scrapers shown, as I reserve to myself the right to use a less or greater number of each without departing from my invention.

Having thus described my invention, what I claim as new, and desire to secure by Letters Patent, is—

1. In a pulverizer, the frame A, the cylindrical roller B, and the scraper D', in combination with the rollers E, adapted to be ad-

justed so as to form a graduated space between themselves and the roller B, substantially as shown and described.

2. In a pulverizer, the combination of the
5 large roller B, the scrapers D, located on either
side of the said large roller, with the roller E',
the semicircular arm fulcrumed in the sides
of the frame A, the rollers E, journaled in said
semicircular arm, the bar f, having a screw-

threaded aperture, and the adjusting-screw, to
substantially as shown and described, and for
the purpose set forth.

In testimony whereof I affix my signature in
presence of two witnesses.

SAMUEL B. FRANK.
